UNITED STATES PATENT OFFICE.

ROBERT BRIGGS, OF PHILADELPHIA, PENNSYLVANIA.

IMPROVED MODE OF FORMING THE CONNECTIONS OF GAS-PURIFIERS.

Specification forming part of Letters Patent No. **90,917**, dated June 8, 1869.

To whom it may concern:

Be it known that I, ROBERT BRIGGS, of Philadelphia, in the county of Philadelphia and State of Pennsylvania, have invented a new and Improved Mode of Making the Connections to Gas-Purifiers; and I do hereby declare the following is a full and exact description thereof, reference being had to the accompanying drawings, making part of this specification, in which—

Figure 1 is a front view; Fig. 2, a top view; Fig. 3, a section on the line *y z*, and Fig. 4 a section on the line *v x*.

The letters of reference in all the figures relate to corresponding parts.

To enable others skilled in the art to make and use my invention, I will proceed to describe its construction and mode of operation.

The main casting *A*, which I call an "inlet and outlet piece," has at the front side two openings, *c d*, to which can be joined inlet and outlet (flow and discharge) pipes to a center seat or valve, or to a system of valves for controlling and operating a set of purifiers, and

has at the back side, opposite *c* and *d*, two openings, *e e*, or hand-holes, so that the body of *A* and the pipes leading from *c* and *d* can be readily cleansed. Within the casting *A*, I form a diaphragm, *f f*, with an annular seat, *g g*, into which seat I affix the stand-pipe *B B*.

The casting *A* being attached to the bottom of a purifier by means of the flange *j*, or otherwise, separate and distinct passages will be then formed for the inflowing gas from the opening *c*, through the seat *g* and pipe *B*, into the purifier, and for escaping gas through the annular space *i i* and the mouth *d* to the center seat or valve.

What I claim as my invention, and desire to secure by Letters Patent, is—

The forming of inlet and outlet connections to gas-purifiers with central and annular openings, or in one casting with passages, substantially as and for the purpose described.

ROBT. BRIGGS.
